AUTOMOTIVE VEHICLE DOOR LATCH

Filed Sept. 18, 1950

UNITED STATES PATENT OFFICE

2,686,416

AUTOMOTIVE VEHICLE DOOR LATCH

Burnie J. Craig, Los Angeles, Calif.

Application September 18, 1950, Serial No. 185,413

9 Claims. (Cl. 70—285)

1

This invention relates to an automotive vehicle door latch.

The general object of the invention is to provide an improved vehicle door latch including novel lock means for controlling release of the latch on a door of an automotive vehicle.

Another object of the invention is to provide door latching means including a novel lock means which is operable in a novel manner to unlock the latch.

Another object of the invention is to provide a novel door latch handle assembly.

Another object of the invention is to provide a novel combined key-controlled and dial actuated tumbler controlled lock assembly.

Another object of the invention is to provide a novel push button operated latch release member and latch lock.

Another object of the invention is to provide a novel push button latch release member including a novel keyless actuated locking member.

A further object of the invention is to provide a latch locking means wherein a push button actuated key lock member is provided and wherein in a dial actuated tumbler member is mounted coaxial with the push button member.

A further object of the invention is to provide a vehicle door latch handle assembly which carries push button means for operating a door latch to release position and wherein a plurality of means is carried by the handle for rendering the push button member inoperative to open the door.

Other objects and advantages of the invention will be apparent from the following description taken in connection with the drawings, wherein:

Fig. 1 is a horizontal sectional view through the door of an automotive vehicle and pillar, with parts in plan and showing the improved automotive vehicle door latch;

Fig. 2 is a fragmentary central sectional view of the handle and latch operating parts;

Fig. 3 is a section taken on line 3—3, Fig. 2;

Fig. 4 is a section taken on line 4—4, Fig. 2;

Fig. 5 is a fragmentary section through a door showing the latch in elevation;

Fig. 6 is a view similar to Fig. 2, showing a modification, and

Fig. 7 is a section taken on line 7—7, Fig. 6.

Referring to the drawing by reference characters, the invention is shown as embodied in a door latch A arranged upon a door B of a vehicle.

As shown, the latch includes a base plate 10,

2

having a pivoted bolt 11 thereon. The bolt supports a strike engaging roller 12 upon its outer end. The latches in the present disclosures are of the type shown in applicant's co-pending application Serial No. 103,431, filed July 7, 1949, now Patent No. 2,659,230, dated November 17, 1953.

The protruding roller 12 moves in a slot 13 in a strike 14 arranged upon the vehicle pillar 15. The slot 13 is inclined (not shown) so that as each vehicle door closes its associated roller moves into the open end of the slot 13 and towards fully engaged position behind a position of the wall of the slot.

15 To hold the bolt in this engaged position and thereby hold the door closed, a catch member 29 (Fig. 5) is pivotally supported upon the base 10. The catch member 29 may be released by a latch releasing member 16 which is slidable on 20 a carriage member 17. When moved in one direction a pin 18 on the latch releasing member engages and rocks the catch member to free the bolt.

The carriage member 17 is pivoted as at 19 on 25 the base 10. One end of the carriage member is raised as at 20 and a snap-over spring 21 is arranged between this raised portion and the base 10 to hold the carriage member in either one of its two positions.

30 The carriage member 17 includes a projecting end 22 which is cylindrical to support a roller 23.

The releasing member and the carriage member are similar to the members described in my patent mentioned above, and a further description thereof seems unnecessary.

35 The releasing member 16 is operated by a releasing arm 25 which is in the nature of a bell crank and is shown as pivoted at 26 upon the base 10. One arm of the bell crank engages in 40 a slot 27 in the releasing member 16 while the other portion of the bell crank is engaged by a tongue 27b on an actuating member 28 which is carried by an outside actuator indicated generally at 30. The outside actuator is similar to the handle assembly disclosed in applicant's prior patent, mentioned above.

45 As shown, the outside actuator or handle assembly 30 includes a body 31 which has a handle grip member 32 thereon. The body 31 may be held in place by means of a slip plate 33 which engages the body 31 and the door.

The body 31 has a chamber 34 and at one end of the chamber has an enlarged bore 35. At the inner end the body is open and enlarged as at 50 36 to receive a closure 37 which is held in place

against rotation by a tight fit and by a split ring 38. The closure 37 engages the end of collar 39 which has an internal flange 40 thereon. The collar 39 is free to rotate.

The body 31 has a bore 41 which receives the tubular dial 42. The body 42 has a finger engaging head portion 43 and an integral external tumbler 44 which engages the end wall of the chamber 34. The dial body includes a reduced portion 42a which rotates within the flange 40.

Concentric with the integral dial tumbler 44, I provide tumblers 45 and 46 which are free to rotate about the dial body portion 42a. The tumblers have the usual tumbler pins 47.

The tumblers are shown as spaced apart by integral collars 48 which are annular and integral with the tumblers. Tumbler locks of this type are common and well known and a further description is believed unnecessary.

The flange 40 (see Fig. 3) is provided with a cut-away part 50 and with ears 51 which support a shaft 53. The shaft 53 supports a carriage shifting or unlocking arm 54 which acts in the manner of a fence and is normally urged to the full line position in Fig. 2 by a spring 55. The arm 54 has one end extending through an arcuate slot 56 in the closure 37.

Rotation of dial head 43 will rotate integral tumbler 44 whereupon the pins on this tumbler will rotate the tumbler 45 and the pins of the tumbler 45 will rotate the tumbler 46.

Each tumbler is provided with a notch or gate 60. The notches or gates 60 are adapted to receive the lower end of the arm or fence 54. The construction is such that after the head portion 43 of the dial has correctly rotated the tumblers, the arm or fence 54 will be aligned with the notches or gates 60, whereupon the spring 55 will move the lower part of the arm or fence into the notches or gates 60.

The tubular dial body 43 slidably receives a lock barrel 61 which includes a push button 62. The push button end extends through a hole 63 in the dial head. The details of the tumbler lock form no part of the present invention as such locks are common and in well known use. The construction is such that when a key 64 is inserted in the barrel 61 and is rotated, suitable pins (not shown) will be aligned, permitting the key to turn the push member relative to the lock barrel through substantially 90 degrees in either direction from a normal position.

The turning of the key rotates a head member 65 on the push member. The head member is connected to and rotates the actuating member 28 previously mentioned. The end of the member 28 is arranged in a slot 28a in the carriage member 17.

In order to prevent rotation of the lock barrel 61 the latter is shown as provided with rods 79 which pass through holes 71 in the fixed closure 37.

The push button may be operated at any time to cause inward movement of the actuating member 28 to thereby rock the bell crank member 25 to cause the latter to move the release member 16. If the carriage member 17 is in unlocked condition, this will cause the release member to release the bolt. If the carriage member 17 is in locked position, the push button and arm 28 will move inwardly without effect.

The key 64 may be inserted and the lock barrel may be rotated to turn the member 28 clockwise or counterclockwise and to cause the inner end of the member 28 to rotate about the axis

of the lock barrel to thus cause the carriage member to be raised or lowered, in other words, to be unlocked or locked. The lock barrel being keyed by the rods 71 to the fixed partition 37, rotation of the lock barrel is prevented.

From the description it will be apparent that a person with a key could rotate the lock barrel and operating member 28 to move the carriage member to unlocked position.

To perform the unlocking operation without rotating the lock barrel and without use of a key, the dial head 43 is rotated to correctly align the tumbler notches so that the arm 54 may be moved by the spring 55 into the notches or gates 60. Thereupon when the dial is rotated the arm 54 will be rotated with the dial about the axis of the lock barrel 61, similar to the motion of the barrel when the latter is rotated by a key.

The carriage shifting arm 54 has a free end 72 which fits in a slot 28a in the carriage member 17 so that when the arm 54 swings it will swing the carriage member from locked to unlocked position.

To limit rotation of the collar 39 the body 31 is provided with a pin 73 which fits in an arcuate slot 74 in the collar 39. A spring 75 engaging the pin 73 normally urges the collar 39 to a central position.

In operation, after the tumbler notches 60 have been aligned, the arm 54 will enter the notches 60. The operator may then turn the dial in either direction to thereby rotate the arm about the axis of the lock barrel. The tension of the spring 55 is such that the arm will, as it turns, shift the carriage member 17 to one limit of its position against the tension of the spring 21. After the carriage member 17 is so moved, further effort to turn the dial head 43 will cause the arms 54 to ride up the sloping side of the notches 60, whereupon the lower end of the arm 54 will be cammed out of the notches 60 and the combination will be unset. When the dial head is then released the spring 75 will return the parts to normal position.

In Figs. 6 and 7 a modification is shown. In the modification parts like those previously described are designated by single primed reference characters. In the modification the arm 54' has no upper part and instead a carriage shifting or unlocking arm 80, shown as integral with the flange 40', is provided. The arm 80 is adapted to fit in the slot 28a in the carriage member 17 in the same manner in which the end 72 of the arm 54 fits in a similar slot in the carriage member.

The operation of the modification is the same as that of the type first described.

From the foregoing description it will be apparent that the invention disclosed herein provides a handle assembly wherein the latch may be released by a push button member and that key operated means permits locking and unlocking. Also that provision is made whereby a dial operated tumbler lock, herein shown for convenience of illustration as coaxial with the push button, permits the lock to be locked and unlocked independently of the key operated lock.

Having thus described my invention, I claim:

1. In a door latch assembly, a chambered body, a support rotatably carried by the body, a lock barrel non-rotatably supported on the body, a head member rotatably carried by the lock barrel and adapted to shift a catch release supporting carriage to and from a position wherein the catch release may be shifted to catch releasing

position, key released means normally preventing relative rotation between the head member and the lock barrel, a series of notched tumblers rotatable in the body, a dial for rotating said tumblers, means operable to clutch the dial and support together for rotation as a unit, said last mentioned means including a fence carried by the support for engaging in the notches of the tumblers when aligned therewith, and a shifting arm movable with the rotatable support, the shifting arm being adapted to shift said catch release supporting carriage to and from said position wherein the catch release may be shifted to catch releasing position.

2. In a door latch assembly, a body having a chamber therein, gated tumblers rotatable in the chamber, a movable fence supported within the chamber and cooperating with the gated tumblers, a dial for rotating the tumblers whereby the tumblers may be positioned with respect to one another and to the fence to allow the fence to enter the gatings of the tumblers and to be moved with the dial and tumblers as a unit, a catch releasing member, a carriage for the catch releasing members, the carriage being shiftable to move the catch releasing member to and from a position wherein the catch releasing member may be shifted to catch releasing position, and an unlocking arm movable with the fence and adapted to move the carriage to the position wherein the catch releasing member may be shifted to catch releasing position.

3. A vehicle door latch including a body having a chamber therein, a catch releasing member, a carriage supporting the catch releasing member, the carriage being shiftable to move the catch releasing member to and from a position wherein the catch releasing member may be shifted to catch releasing position, a series of tumblers formed with gatings and rotatable in the chamber, a dial for rotating said tumblers, a movable fence operative when the tumbler gatings are properly disposed to clutch the dial to the carriage whereby movement of the dial will move the carriage and shift the catch releasing member to the position wherein the catch releasing member may be shifted to catch releasing position.

4. In a vehicle door latch, a chambered body, a support rotatable within the body, a lock barrel non-rotatably supported on the body, a catch releasing member, a movable carriage supporting the catch releasing member for movement to and from catch releasing position, a head member rotatably carried by the lock barrel and operable to move the carriage and catch releasing member to a position wherein the catch releasing member may be shifted to catch releasing position, key released means normally preventing relative rotation between the head member and the lock barrel, a series of notched tumblers rotatable in the body, a dial for rotating said tumblers to align the notches, means operable to clutch the dial and support together for rotation as a unit, said means including a fence carried by the support for engaging in the notches of the tumblers when aligned therewith, and a carriage shifting arm movable with the rotatable support and operable to shift the carriage to the position wherein the catch releasing member may be shifted to catch releasing position when the dial and support are so clutched together and the dial is turned.

5. A vehicle door latch including a body having a chamber therein, a catch releasing mem-

ber, a carriage movably supporting the catch releasing member for movement to and from a catch releasing position, the carriage being shiftable to move the catch releasing member to and from a position wherein the catch releasing member may be shifted to catch releasing position, notched tumblers rotatable in said chamber, a dial for shifting the tumblers, movable clutch means including a fence operative when the tumbler notches are aligned with the fence to clutch the dial to the carriage whereby movement of the dial will move the carriage and shift the catch releasing member to the position wherein the catch releasing member may be shifted to catch releasing position, said dial including a portion for engagement with the fingers of an operator to permit rotation of said tumblers for aligning the notches and for rotating said tumblers for shifting the carriage when the dial and carriage are clutched together, a push button slidable within said chamber, and a latch actuating member carried by said push button, the latch actuating member being operable to actuate the catch releasing member to the catch releasing position.

6. A vehicle door lock including a body having a chamber therein and having a bore communicating with the chamber, a catch releasing member, a movable carriage movably supporting the catch releasing member for movement to and from a catch releasing position, the carriage being shiftable to move the catch releasing member to and from a position wherein the catch releasing member may be shifted to catch releasing position, a dial member rotatable in said bore and having peripherally notched tumblers thereon, a rotatable member within said body, an arm pivoted on said rotatable member, the tumbler notches receiving said arm when the notches are aligned therewith for clutching the dial member to the rotatable member for rotation as a unit, means normally urging the arm into the tumbler notches, an unlocking arm rotatable with said rotatable member and adapted to shift the movable carriage and move the catch releasing member to the position wherein the catch releasing member may be shifted to catch releasing position, said dial member including a portion for engagement with the fingers of an operator to permit rotation of said tumblers for aligning the notches and for rotating said tumblers and said rotatable member as a unit when the tumbler notches are aligned with the fence, a push button slidable within said dial member, and a latch actuating member carried by said push button, the latch actuating member being operable to actuate the catch releasing member to the catch releasing position.

7. In a door latch assembly, a body having a chamber therein, gated tumblers rotatable in the chamber, a movable fence supported within the chamber cooperating with the gated tumblers, a dial for rotating the tumblers whereby the tumblers may be correctly position with respect to one another and to the fence to allow the fence to enter the gatings of the tumblers and to be moved with the dial and tumblers as a unit, a catch releasing member, a movable carriage supporting the catch releasing member, the carriage being shiftable to move the catch releasing member to and from a position wherein the catch releasing member may be shifted to catch releasing position, an unlocking arm movable with said unit to move the carriage to the posi-

tion wherein the catch releasing member may be shifted to catch releasing position, a push button, and a latch actuating member actuated by the push button and operable to move the catch releasing member to the catch releasing position.

8. In a door latch assembly, a chambered body, a support rotatably carried by the body, a lock barrel non-rotatably supported on the body, a catch release member, means movably mounting the catch release member for movement to and from a position in which the catch release member may be shifted to catch releasing position, a head member rotatably carried by the lock barrel and adapted to shift the catch release member to and from said position in which it may be shifted to catch releasing position, key release means normally preventing relative rotation between the head member and the lock barrel, a series of notched tumblers rotatable in the body, a dial for rotating said tumblers, means operable to clutch the dial and support together for rotation as a unit, said last mentioned means including a fence carried by the support for engaging in the notches of the tumblers when aligned therewith, and a shifting arm movable with the rotatable support, the shifting arm being adapted to shift said catch release member to and from said position wherein the catch release member may be shifted to catch releasing position.

9. In a door latch assembly, a chambered body, a support rotatably carried by the body, a lock barrel non-rotatably supported on the body, a catch release member, means movably supporting the catch release member for movement to and from a position wherein the catch release member may be shifted to catch releasing posi-

tion, a head member rotatably carried by the lock barrel and adapted to shift the catch release member to and from said position in which it may be shifted to catch releasing position, key release means normally preventing relative rotation between the head member and the lock barrel, a series of notched tumblers rotatable in the body, a dial for rotating said tumblers, means operable to clutch the dial and support together for rotation as a unit, said last mentioned means including a fence carried by the support for engaging in the notches of the tumblers when aligned therewith, and a shifting arm movable with the rotatable support, the shifting arm being adapted to shift said catch release member to and from said position wherein the catch may be shifted to catch releasing position, a latch actuating member operable to move the catch releasing member to catch releasing position and means operable to move the latch actuating member to cause the catch releasing member to move to catch releasing position.
